UNITED STATES PATENT OFFICE.

AMOS H. HAWLEY, OF NORWOOD, OHIO, ASSIGNOR TO INTERNATIONAL MONEY MACHINE COMPANY, OF TERRE HAUTE, INDIANA.

ACCOUNTING-MACHINE WITH AUXILIARY PRINTING APPLIANCE.

1,396,932.

Specification of Letters Patent.

Patented Nov. 15, 1921.

Application filed May 15, 1917. Serial No. 168,688.

To all whom it may concern:

Be it known that I, AMOS H. HAWLEY, a citizen of the United States, residing at Norwood, in the county of Hamilton and State of Ohio, have invented certain new and useful Improvements in Accounting-Machines with Auxiliary Printing Appliances, of which the following is a specification.

In many businesses, especially those employing a large number of wage earners, adding and listing machines are used to a considerable extent in facilitating the making up of pay-rolls.

An object of this invention has been to supply certain equipment and mechanism for such accounting machines to enable envelops in which amounts of wages are paid to employees to be readily printed with an amount of wages at the same time as the said amount is listed on the customary paper tape or strip utilized for list printing in machines of this type.

With the foregoing in view, it is contemplated to provide a duplicate set of printing devices, similar to those used for ordinary listing but modified to conform with peculiar special requirements. There is also provided for the envelop printing a suitable holding device for the envelop. The envelop printing instrumentalities and equipment is susceptible of advantageous use for duplicate printing of transactions whether the duplication is made upon envelops, slips, checks, or the like; when upon the envelop itself, the duplicated item is very useful to the pay-roll worker for obvious reasons.

A further object of the invention is to provide convenient adjusting devices for the envelop, tag, or slip holding means whereby the latter articles may properly support the articles placed therein when of different sizes in respect to various dimensions.

The improvements of this invention comprehend, additionally, provisions for controlling the elimination of the printing functioning of the listing instrumentalities of the machine. These provisions appertain in the first instance to the disabling of the regular or main printing devices used for listing amounts of transactions of the machine upon the usual tape or listing strip, and to the auxiliary printing devices intended to per-

form the duplicate printing previously referred to herein.

By the disabling means just mentioned, it is possible to eliminate the printing functioning of one or both of what may be termed the main and auxiliary sets of printing members so that where the accounting machine is an adding and listing machine the listing functioning of the machine may be temporarily discontinued permitting of the use of the machine as an adding or an accumulating machine alone. Again, it is contemplated, secondary to the foregoing, to so interlock the disabling devices for the main and auxiliary sets of printing devices as to cause the auxiliary or duplicate set of printing members to be disabled as an incident to the rendering inoperative of the main or customary listing printing members; on the other hand, the construction is so designed that the means employed to render inactive the auxiliary printing members may perform its function without disturbing the operativeness of the main listing instrumentalities in any way.

The invention involves supplemental to the foregoing main features, certain details of construction which will appear more fully upon reference to the following description in connection with the accompanying drawings, in which:

Figure 1 is a general front elevation of an adding and listing machine of the type to which the invention is applied.

Fig. 2 is a top plan view of the machine illustrated in Fig. 1, partly broken away.

Fig. 3 is a fragmentary sectional view looking from the front of the machine toward the rear with the section taken somewhat in advance of the various type-carriers of the main and auxiliary sets or groups of printing instrumentalities, the means interlocking these groups for simultaneous and independent disablement being clearly shown.

Fig. 4 is a view showing primarily the parts illustrated in Fig. 3, being a fragmentary section looking toward said parts from the right hand side of the machine.

Fig. 5 is a view in elevation showing more particularly the reverse arrangement of the

types of the main and duplicate sets of type-carriers.

Fig. 6 is a horizontal sectional view taken through the envelop holding means including the back plate of the machine.

Fig. 7 is a detail view somewhat similar to Fig. 4 bringing out clearly the form of the main elimination key and its associated disabling bail.

10 Fig. 8 is a detail perspective view showing more clearly the formation of the upper end of the envelop guide.

It may be noted that the adding and listing machine of the present invention embodies primarily a mechanism such as is shown in the U. S. Letters Patent of Nelson White, No. 1,192,721, issued April 25, 1916. Since the general arrangement of the accumulating and listing means of the present invention is like that of the said White patent, the same will not be described in detail other than to bring out the modifications in the prior patented construction necessitated to conform to the purposes of the present improvements, together with the various additional features which represent novelty of this invention alone.

Referring to the drawings, the adding machine casing is designated A and is equipped with the usual amount keys 1 adapted to control the setting up of the transactions to be performed upon the machine, the customary main actuator or handle 2 being utilized for operating the accumulating and listing mechanisms in accordance with amounts predetermined by the keys 1. The totalizing actions of the machine are controlled by special keys as customary. For the purposes of the present invention there is provided at the back of the machine and suitably attached to the back plate 3 an envelop guide plate 4, see Figs. 3 and 4. This plate is provided with a flange 5 at its left-hand edge and is secured in place on the back plate 3 by means of the thumb screw and nut connection designated 6, as well as by the corresponding connections designated 7, see Figs. 3 and 6. The thumb screw of the connection 6 passes through a horizontal slot in the back plate 3 and through an opening in the flange 5 of the guide or plate 4. In like manner the thumb screws of the connections 7 pass through slots in the back plate 3 and through openings in the front guide plate 4, there being interposed between the right-hand portion of the plate 4 and the back plate 3 a spacing plate 8, which in coöperation with the flange 5, uniformly spaces the plate 4 from the back plate 3. The spacing is, of course, provided to facilitate the entering of an envelop, slip, tag, or like article, between the plates 3 and 4 and between the plate 4 and the platen 9, seen best 65 in Fig. 4, the entering being, of course, for

the purpose of printing an amount of a transaction upon said article.

By the provision of the method of connection of the plate 4 with the back plate 3, involving the use of the fastenings 6 and 7, 70 it will be apparent that it is possible to move the guide plate 4 bodily slightly to the right or to the left as regards its position illustrated in Fig. 3. In this way the left-hand extreme of the guide space for 75 receiving the envelop or similar article may be varied slightly in relation to the duplicate or auxiliary printing instrumentalities to be shortly described. Furthermore the spacing plate 8 is obviously adjustable 80 slightly to the left so as to permit larger or smaller envelops to be accommodated in the guide or holding means, and the upper end of the plate 8 is cut away on an outward curve, somewhat after the manner of 85 the bent formation of the upper portion of the flange 5 to provide an outwardly flaring entrance to the envelop guiding or supporting means. To control the degree of entering movement of an envelop or similar article into the guide or holder provided as above described there is supplied a gage plate 10 secured adjustably to the back plate 3 by a fastening 11 similar to the fastenings 6 and 7, see Fig. 3. The fastening 11 95 passes through a slot in the gage plate 10 and the latter is held from lateral shifting by two studs 12 on the back plate 3. At its upper end the plate 10 enters the space between the plates 3 and 4 and the manner 100 of performance of its function is obvious from the foregoing.

Main and auxiliary printing devices.

The arrangement of these devices is somewhat similar to the corresponding arrangement of similar parts set forth in the White patent above identified. The main printing devices comprise the type-carriers 13 and the auxiliary printing devices include the 110 type-carriers 14. These type-carriers are operated differentially by known means and are similar in all respects to one another excepting that the type of the carriers 14 are inverted, whereas the type of the main carriers 13 are of usual form and arrangement. The inversion of the type of the carriers 14 is necessitated because the envelop is introduced into the guide or holder therefor in such a manner that the printing is 115 reversed or inverted. It is on this account that a slightly different arrangement of the means for transmitting motion from the main units type carrier to the auxiliary units type carrier is employed. The motion transmitting means between the main and auxiliary type-carriers involves the provision of the horizontal shafts 15, as heretofore known, with pinions on these shafts, the pinions of one shaft engaging corre- 130

sponding type bars, such as the corresponding units or tens type bars of the main and auxiliary type-carriers. The main type carriers are actuated differentially and their differential movement is imparted to the auxiliary type carriers by the shafts 15 and pinions 15^a. Owing to the inversion of the type of the type-carriers 14, the main units type carrier is connected, as seen in Fig. 3, 10 with the outermost type-carrier 14 which is the units auxiliary type carrier, the main tens type-carrier 13 is connected with the second from the outermost carrier 14, and so on.

15 Referring now to Figs. 4 and 7, the means for controlling simultaneous and certain independent operation of the main and auxiliary type carriers will be described.

The printing means as shown in Figs. 20 3 and 4 is largely conventional involving the use of customary printing hammers 16 and the hammer drivers 17 each having an arm connected by the lugs 17' with an associated hammer, and having a tail 17'' 25 connected with an operating spring 18. There are supported for coöperation with the various hammers 16 the usual catches 18^a carried by the shaft 19 supported by a frame including the depending arms 20.

30 The said frame is adapted to be oscillated under the action of means coöperating with a lever arm 20' forming an extension of one of the arms 20 of said frame, the parts 20 and 18 being susceptible of movement 35 such that the catches 18^a may be engaged with lugs 21 on the tails of the hammer drivers. When thus engaged the catches 18^a are adapted to be moved by the shaft 19 to pull downwardly upon the hammer drivers placing the springs 18 under tension, the hammers being fired as an incident to engagement of the lower ends of the catches 18^a with abutments 22 which are formed upon the inner edges of the various 40 type-carriers 13 and 14. It will be understood that the parts 16 and 20 are coaxially mounted, and the frame including the arms 20 is oscillated at each operation of the machine by the main actuator or handle 45 2. Thus if the catches 18 are not interferred with in their normal operation they will cause firing of the hammer 16 by release of the hammer drivers, every time the handle 2 is operated. The hammers 16 50 operate upon types of the type carriers 13 and 14, which types have been raised to proper adjustment during the initial movement of the handle previous to the firing of said hammers. In the rear of the main 55 and auxiliary type carriers 13 and 14 are located the main and auxiliary disabling bails 23 and 24 respectively. These bails, seen best in Figs. 3 and 4, are of somewhat comb-like form, each bail having teeth 60 adapted to engage the upper ends of the adjacent catches 18^a. The bails 23 and 24 are really slotted plates, the ends of which are bent over to form flanges, there being provided a supporting shaft 25 passing through said flanges and forming the axis 70 of movement of the bails as seen in Fig. 4. An auxiliary eliminating key 26 normally held elevated by a spring 26' is provided and is formed with a triangular opening, a wall of which, designated at 26'', 75 forms a cam engaging stud 27 on the right end of the bail 24, see Fig. 3. The depression of the key 26 will cause the cam 26'' to engage the stud 27 and work the bail 24 so that the teeth of the latter are shifted 80 rearwardly in such a way as to prevent the noses of the catches 18, coöoperative with the auxiliary type hammers from engaging the studs 21 on the adjacent hammer drivers 17. Obviously under these conditions the 85 actuation of the catches 18 for the auxiliary hammers 16 is rendered ineffective thus disabling these hammers while the key 26 is depressed. The key 26 is held depressed by a notch 26^a thereof engaging a guide 90 plate 28 through which the key passes.

Referring to Fig. 3 it will be seen that there is provided a main eliminating key 29 having a cam slot 29'', an upraising spring 29' (see Fig. 7). The slot 29' 95 receives a stud 30 equivalent to the stud 27 previously described, and the action of the key 29 when depressed is obviously similar to that of the key 26 respecting the rocking of the bail 23, which carries the 100 stud 30. The disablement of the main type hammers associated with the carriers 13 is thus effected by the key 29.

As seen in Fig. 3, the left flange of the bail 24 is interrupted at its upper portion 105 to provide a lug 31 entering a cut-away portion of the bail 23 in rear of the right flange of the bail 23, engaging the upper end 32 of said flange. This arrangement provides the interlocking functioning of the 110 parts 23 and 24 heretofore referred to so that the following control actions of the eliminating keys are obtainable: A depression of the auxiliary key 26, enables the disablement of the auxiliary type hammers 115 16 and the elimination of the listing functioning of the duplicative printing instrumentalities. The action of the bail 24 is independent of any operation of the bail 23. On the other hand, if the key 29 be de- 120 pressed to disable the main type hammers 16 and the main printing instrumentalities, the rocking of the bail 23 through the coaction of the members 31 and 32 causes simultaneous rocking of the bail 24 to disable 125 the auxiliary type hammers 16. The movement of the auxiliary bail 24 with the bail 23 is allowed by the key 26 owing to the clearance afforded by the formation of the triangular opening in the key 26. 130

- Summarizing, therefore, it is to be understood that the main and auxiliary printing instrumentalities are such that they may be controlled in action for the purpose of 5 disabling the auxiliary or duplicative printing members without affecting the action of the main printing members; or the control may be such that the auxiliary printing members may be disabled at the same time 10 as the main members are incapacitated to perform their function. The means for holding the main eliminating key 29 depressed are the same as the means described in reference to the key 26.
- 15 The term "bail" as used herein as applicable to the members coacting to interrupt the normal operating of the catches 18, is to be understood as comprehending any camming devices operating to accomplish the 20 described result. I therefore do not wish to limit myself to the bails as necessary constructional elements except with the reservation that they or equivalent parts may be utilized by me.
- 25 Having thus described my invention, what I claim as new is:
1. In an accounting machine, the combination of listing mechanism including main and auxiliary printing devices, actuating 30 means for said devices, main and auxiliary disabling bails for said main and auxiliary printing devices respectively, and means to operate each of said bails and to operate one bail from the other.
  - 35 2. In an accounting machine, the combination of listing mechanism including main and auxiliary printing devices, actuating means for said devices, main and auxiliary disabling bails for said main and auxiliary 40 printing devices respectively, and means to operate each of said bails and to communicate operating movement from one bail to the other.
  - 45 3. In an accounting machine, the combination of listing mechanism including main and auxiliary printing devices, actuating means for said devices, main and auxiliary disabling bails for said main and auxiliary printing devices respectively, means to operate each of said bails, and interengaging means intermediate the bails.
  - 55 4. In an accounting machine, the combination with listing mechanism including a plurality of main printing devices and a plurality of separate auxiliary printing devices, of a main member cooperative with the main printing devices to prevent operation thereof, and a corresponding auxiliary member cooperative with the auxiliary printing devices 60 to prevent operation of the same, means to move one of said members to active position, and means to communicate movement of said member to the other member.
  - 65 5. In an accounting machine, the combination of listing mechanism including main and auxiliary printing devices, actuating means for said devices, coaxial disabling bails for said actuating devices, and means to operate either bail to cause it to perform its disabling function, the last means including 70 an instrumentality adapted to cause simultaneous operation of the bails.
  - 75 6. In an accounting machine, the combination of listing mechanism including printing devices, said devices comprising type carriers and types thereon, type hammers, hammer drivers for said hammers, catches to set and fire said drivers, engaging means between the catches and drivers, a disabling bail to engage the catches and prevent action 80 thereof on the drivers, and a key to actuate and hold the bail operative.
  - 85 7. In an accounting machine, the combination of listing mechanism including printing devices, and an article holder therefor comprising a guide plate and its support, means to adjust the plate on the support, and means whereby to vary the operative guiding surface of the plate, both transversely and longitudinally.
  - 90 8. In an accounting machine, the combination of listing mechanism including printing devices, and an article holder therefor, comprising a guide plate and its support, and means whereby to vary the operative guiding surfaces of the plate including an adjustable member at one edge of said plate.
  - 95 9. In an accounting machine, the combination of listing mechanism including printing devices, and an article holder therefor, comprising a guide plate and its support, means whereby to vary the operative guiding surfaces of the plate including an adjustable member at one edge of said plate, and a gage plate adjustable cooperatively with the guide 100 plate at substantially a right angle thereto.
  - 105 10. Listing mechanism for accounting machines, comprising a plurality of type carriers, types on said carriers, actuating devices for the types, bails to disable the said actuating devices, and independently operable keys to actuate one or more of said bails.
  - 110 11. In an accounting machine, listing mechanism including a plurality of series of printing devices, a main disabling key for one of the said series of devices, an auxiliary disabling key for another series of said devices, separate disabling parts operable by the said keys, and means operable from said keys to control separate and simultaneous action of the disabling parts aforesaid.
  - 115 12. In an accounting machine, listing mechanism including a plurality of printing devices, a main disabling key for one of the said devices, an auxiliary disabling key for another of said devices, separate disabling parts operable by the said keys, and means intermediate the disabling parts operable to effect simultaneous action of the disabling parts on operation of one of the keys and 130

permitting action of one of the disabling parts alone on operation of the other key.

13. In an accounting machine, the combination of listing mechanism including main and auxiliary series of printing devices, actuating means for said series of devices, main and auxiliary cam devices for said main and auxiliary series of printing devices respectively, and means to operate either of said 5 cam devices and to operate one cam device from the other to change the operative condition of the printing devices.

14. In an accounting machine, the combination of listing mechanism including printing devices, said devices comprising type-carriers and types thereon, type hammers, hammer drivers for said hammers, catches to set and fire said drivers, engaging means between the catches and drivers, a cam device to engage the catches and prevent action 15 thereof on the drivers, and a key to actuate and hold the cam device operative.

In testimony whereof I affix my signature.
AMOS H. HAWLEY.
